Primary Examiner—Caron Veynar*Assistant Examiner*—Garth Rademaker(74) *Attorney, Agent, or Firm*—Vedder Price P.C.; W. Dennis Drehkoff(57) **CLAIM**

The ornamental design for a lid removal element, as shown and described.

DESCRIPTION

FIG. 1 is a perspective view of a lid removal element showing my new design;

FIG. 2 is a side elevation view thereof;

FIG. 3 is an opposite side elevation view thereof;

FIG. 4 is a top plan view thereof;

FIG. 5 is a bottom plan view thereof;

FIG. 6 is a rear elevation view thereof; and,

FIG. 7 is a front elevation view thereof.
